UNITED STATES PATENT OFFICE.

WALTER J. CLARKE, OF SAN FRANCISCO, CALIFORNIA.

SAFETY-FAUCET.

1,032,044.

Specification of Letters Patent. Patented July 9, 1912.

Application filed June 8, 1911. Serial No. 632,016.

To all whom it may concern.

Be it known that I, WALTER J. CLARKE, a citizen of the United States, residing in the city and county of San Francisco and State 5 of California, have invented new and useful Improvements in Safety-Faucets, of which the following is a specification.

This invention relates to cocks and faucets for use on containers for gasoline and other 10 volatile liquids.

The object of the invention is to provide a simple, cheap, practical, automatically closing, tight-seating faucet, which can be readily applied to tanks and cans for containing gasoline and the like, which faucet will not open in case the can is upset and from which faucet all packing glands are eliminated.

The invention consists of the parts and 20 the combination and construction of parts as hereinafter more fully described and claimed having reference to the accompanying drawings, in which—

Figure 1 is a longitudinal section of the 25 faucet showing its application to a container. Fig. 2 is a section of the faucet body. Fig. 3 is an end view of the same. Fig. 4 is a detail of the springs. Fig. 5 is an end view of the entire device. Fig. 6 is a section of the 30 flange. Fig. 7 is an end view of the same. Fig. 8 represents details of the sealing lid. Fig. 9 represents details of the valve. Fig. 10 represents details of the operating key. Fig. 11 is a detail of the conical plug.

35 A represents a tank or can, or other container, which may be either of the horizontal or of the vertical type as here shown.

2 is a flange which is bolted, or otherwise suitably secured to the can and on to which 40 flange the body 3 of the faucet is adapted to be screwed.

4 is a spout.

5 is the valve seat for the valve 6, and 7 is a chamber in the outer end of the faucet 45 body forming a housing for the key 8, the plug 9 and spring 10. Valve 6 has a stem 11 sliding in the spider-guides 12 in flange 2.

13 is a spring operative to keep the valve 6 normally closed against its seat 5. Valve 50 6 has a hollow or tubular stem portion 14 projecting into the spout passage, and in axial line with a reduced bore 15 of the faucet body. Into this hollow or tubular portion 14, the inner end of the key 8 fits and

is guided. The key 8 has an expanded cylindrical portion 16 between its ends normally fitting and closing the passage 15 in the body 3.

17 is a hinged sealing cap by which the chamber 7 may be sealed, as indicated at 18, 60 and the key protected against being tampered with.

In operation the cover 17 is unlocked and lifted and the key 8 pushed in until it strikes the bottom of the cavity in the tubular projection 14 to open the valve 6 whereupon the liquid can flow out of the spout. At the same time that the key is pushed in the conical plug 9, which has a snug sliding fit on the key stem is carried forward into its conical seat at the reduced end of the chamber 7, so as to prevent the liquid spurting out into chamber 7, around the key; spring 10 allowing for a limited movement of the key inwardly to open the valve after the plug 9 is 75 fully seated. On the release of pressure on the key 8 the combined action of the spring 13 and the liquid pressure in the tank closes valve 6 snug on its seat 5, and the spring 10 retracts the key so that it is normally out of 80 operative engagement with the valve. Whenever the cover 17 is closed down over the key and locked the tank can be turned up side down, or rolled over without any liability 85 of the valve being opened or unseated.

Having thus described my invention, what I claim and desire to secure by Letters Patent is—

1. In a faucet the combination of a cylindrical body, one end shaped to form a housing for a key, the other end shaped to provide a valve seat, a spout between the ends, a valve fitting said seat and controlling discharge to said spout, a key in said housing operative on the valve, and a plug and a seat 90 therefor, said plug being loosely mounted on the key and adapted to prevent the liquid from entering said housing when the key is operated to open the valve.

2. The combination with a can, of a flange 100 secured thereto, a faucet body secured to the flange, said faucet body having a passage-way opening through the flange into the can, a valve supported by said flange and operative to close said passage-way, a key supported in the outer end of the faucet body and telescoping with the valve, a plug carried by and slidable relative to the key, said

faucet body having a separate seat for the plug, and independent springs one acting upon the valve and the other upon the plug and both yieldable in the same direction whereby the plug is seated when the valve is unseated.

In testimony whereof I have hereunto set

my hand in the presence of two subscribing witnesses.

WALTER J. CLARKE.
